UNITED STATES PATENT OFFICE

RUDOLPH W. MENK, OF JOLIET, ILLINOIS

SECTIONAL BOILER FURNACE

Application filed August 13, 1926. Serial No. 128,994.

My present invention relates to furnaces of the boiler type and has more particular reference to a structure of this character that is separately formed in opposing sections so that the same may be shipped in knock-down form and assembled at the place of installation.

The present structure is made preferably from sheet metal plates that are brazed, welded or otherwise secured together and the outfit is made in two semi-cylindrical sections so that they may be assembled in opposition to each other to provide a complete cylindrical structure when completed. With my present invention I am enabled to provide a structure that in its knock-down form may be readily handled and may be passed through small openings in a building thereby avoiding the necessity of having to deliver and install the furnace while the walls of the building are under construction. Also the parts are so arranged for assembly that the respective sections may be spaced apart by means of an intermediate section for the purpose of enlarging the capacity of the furnace whenever desired. The arrangement and disposition of the parts are such that I secure a greater area of heating surface for the water, and by the employment of certain instrumentalities I have been able to create a longer draft or path to be traversed by the products of combustion while at a high temperature. Among the divers objects of my invention are the provision of a structure of this character that embodies dependability in operation, economy in manufacture, compactness in construction, and novelty in the arrangement and disposition of the parts. I prefer to carry out my invention and to accomplish the divers objects thereof in substantially the manner hereinafter fully described and as more particularly pointed out in the claims, reference being made to the accompanying drawings that form a part hereof.

In the drawings:

Figure 1 is a central vertical section through the body of the furnace showing the arrangement and disposition of divers parts thereof.

Figure 2 is a vertical side elevation of the complete furnace installed.

Figure 3 is a vertical elevation of the rear semi-cylindrical section, looking at the same from the hollow side thereof.

Figure 4 is a view similar to Figure 3 illustrating the front semi-cylindrical section.

Figure 5 is a horizontal transverse section taken on line 5—5 of Figure 2 and looking in the direction of the arrows.

Figure 6 is a fragmentary transverse section on about the plane of Figure 5 showing the manner of increasing the dimensions of the furnace by means of an intermediate section.

Figure 7 is a vertical fragmentary section taken on line 7—7 of the structure illustrated in Figure 6.

As will be seen, the furnace is formed from two cylindrical hollow sections A and B. The former section A is the front section in which is provided the usual openings for the fuel, for the clean-out and for access to the grate bars and the other section B is the rear section which is provided with an outlet 10 for the discharge of the products of combustion to the chimney flue. The semi-cylindrical sections A and B are provided, adjacent their edges, with lateral ears or lugs 11 arranged in planes opposite each other and adjacent the upper and lower portions of the respective sections, which lugs are provided with apertures through which clamping bolts 12 are passed, so as to draw the sections tightly together. These sections are preferably formed of sheet metal plates, the vertical walls 13 and 14 being disposed parallel or concentric to each other to provide outer and inner spaced walls between which there is a chamber 15 for the circulation of water. The lower edges of these plates are connected by annular bottom rings 16 so as to close the lower portions of the water-chambers 15 and said sections are mounted upon and supported above the floor upon the usual base that provides an ash box 17 (Figure 2). At their upper end portions the double walls are continued over laterally in a horizontal direction to provide the upper and lower spaced walls 18 and 19.

of suitable domes, which provide the closures for the upper portion of the furnace and which are semi-circular in outline, with their outer and inner walls 18 and 19 spaced apart 5 a greater distance than in the cylindrical portion of the structure to provide an enlarged water space above the fire pot.

The cylindrical sections with their domes are independent of each other, the dome 10 walls being connected by vertical end plates 20 that are set back slightly from the edges of the upper and lower walls thereof so as to provide shallow recesses for the reception 15 of a suitable furnace cement 21 that is placed therein while in a plastic condition and compressed and spread by the clamping action of the bolts 12 when the respective sections A and B are drawn together. Similar vertical separator walls or end plates 22 spaced 20 back of the vertical edges of the semi-cylindrical walls 13 and 14 provide similar recesses along the vertical portions of the sections A and B for the reception of the cement 23, so that the joint between 25 the respective sections is rendered air-tight and gas-tight after assembly in the manner above described. The sections A and B, on account of their small transverse dimensions may be readily inserted through a small cellar window or carried separately through a narrow cellar door of a building where it is desired to install the furnace, without the inconvenience of having to knock out portions of the wall of 30 the building as is so often the case with furnaces made of an integral cylindrical shape.

The sections A and B including their domes do not communicate with each other, as will be obvious from the foregoing description, because of the walls or end plates 40 20 of the domes and the walls or end plates 22 of the cylindrical portions of the sections, but in order to obtain a distribution of the steam or hot water from the sections, the 45 domes are provided with outlets 24 into which suitable pipe connections 25 are screwed that lead to a union or T-coupling 26 so that the steam or hot water arising from the cylindrical portions into the domes 50 will pass out through the above described connections and be distributed from the T-coupling to leads and radiators in the heating system.

The front section A is provided with a 55 water-chamber X that projects inwardly from the inner wall 14 of this section in a plane above the fuel opening and said chamber X is formed by a horizontally disposed plate 27 that extends across the entire section and projects inwardly to a point inside 60 the plane of the edges of the cylindrical wall 14 of the front section where said plate is "nosed" or curved outwardly and upwardly as at 28 and continues as an upwardly inclined wall 29 to the inner wall 14 of the

front section where it is joined thereto in a plane below the clean-out opening in the upper portion of said section. When observed in vertical cross section, the water chamber X is of triangular shape with its 70 base horizontally providing the bottom wall of the chamber and its hypotenuse is inclined from the inner edge of the base upwardly and provides the top wall of the chamber. This chamber is so constructed and positioned that the products of combustion arising from the fuel upon the grates will strike the bottom wall 27 and be deflected away from the front cylindrical wall 14 toward the rounded edge or "nose" 28 and 80 then pass upwardly against the walls 10 of the semi-circular domes and out through the outlet 10 of the section B.

The rear section B of the structure is provided with a water-chamber Y, the walls of 85 which are disposed in reversed relation to those of the chamber X and comprise a horizontal top plate or wall 30 that projects from the inner wall 14 of the section B toward the edges of the cylindrical section where the 90 plate forming said wall is "nosed" or rounded outwardly and downwardly as at 31 and continues in a downwardly inclined direction to provide the oblique bottom wall 32 which terminates at and is secured to the inner wall 14 95 of the section B. As seen, the chamber Y is also of triangular shape in cross section, the base of the triangle in this instance being uppermost and the hypotenuse provides the lower wall of the chamber, the said structure 100 being thereby a reversal of the arrangement of the chamber of the front section A. It will also be seen that the inclined or oblique walls 29 and 32 of the chambers are substantially parallel to each other as are also the horizontal walls 27 and 30, and the so-called "nose" portions 28 and 31 are separated from each other and disposed one above the other so as to provide an elongated passageway 33 of restricted dimensions through which the 105 products of combustion must pass and beyond the passageway they enter the upper portion Z of the furnace which, as will be seen, is of greater dimensions and capacity than the passageway so that they linger in ignited 110 condition prior to leaving the structure. In order to assist combustion in this upper portion Z the door of the upper opening x may be opened for the admission of air thereto. The inclined wall 32 of the 115 chamber Y deflects the products of combustion upwardly and forwardly toward the other chamber X so that the path of the products of combustion is circuitous and these hot gases are brought into intimate contact with 120 a considerable area of heating surface in the furnace. The inclined walls 29 and 30 will, of course, shed off dust, soot and foreign matter due to their slope and the horizontal wall 30 of the chamber Y may be readily cleaned 125 130

of the soot, etc., by means of a scraper or other device inserted through the upper opening ²⁵ above the upper edge of the inclined wall 29.

In order to baffle or retard the flow of the products of combustion and to divide the same in the combustion chamber to cause the hot gases to engage the side walls in the upper portion of the structure, I have provided one or more tubes 34, (preferably two), that are positioned vertically upon the inner edge portion of the top horizontal wall 30 of the upper chamber, in front of the outlet 10 and which extend upwardly to the inner lower wall 19 of the dome of the rear section B. ¹⁹ These tubes are water-contained and establish connection between the chamber Y and the dome above the same, and the space between the tubes may be closed by placing therein suitable fire brick 35 so that said brick and ²⁵ tubes provide a baffle in front of the discharge outlet and prevent a direct flow of the gases to the outlet.

The return water from the radiators and lead pipes is fed back into the lower portions ²⁵ of the sections A and B by means of a union or T-coupling 36 upon each side of the furnace at about the location of the joint between the respective front and rear sections A and B (Figures 2 and 5), and from these couplings the water passes into the cylindrical water-chambers 15 through inlet stubs 37 on the respective sections.

From the outlet 10 the products of combustion pass into the flue or pipe 38 leading to the chimney, which pipe is provided with a vertically disposed offset portion 39 that is divided longitudinally in a vertical direction by a partition 40 that extends down below the plane of the lower edge of the outlet ⁴⁰ 10 and provides a down passageway 41 and an up passageway 42 upon opposite sides thereof. The construction just described is controlled by means of a butterfly damper 43 that may be adjusted to permit the products of combustion to flow either straight into the chimney flue or downwardly through the passages 41 and 42 which latter will somewhat retard its flow and thereby retain the heated products within the confines of the furnace for a longer period than when the draft or flow is direct to the chimney.

In Figures 6 and 7 there is illustrated the manner of increasing the capacity of the boiler furnace by interposing an intermediate section C between the facing or abutting edges of the semi-cylindrical sections and domes. When it is desired to employ the intermediate section C, the clamping bolts 12 are released and the abutting edges of the sections A and B separated a distance sufficient to permit the insertion of the intermediate section, after which longer bolts are inserted in the lugs 11 and the structure firmly and tightly drawn together. The intermediate section C comprises spaced parallel vertical

walls 13^a and 14^a that provide continuations of the respective inner and outer walls of the semi-cylindrical sections A and B and the edges of these vertical walls are connected by the closure walls 20^a so as to provide a shallow recess on each side of the intermediate section facing the recesses or depressions in the edges of the sections A and B and afford a space in which the cement 23 may be placed in order to provide air-tight and gas-tight joints ⁷⁰ where the sections are clamped together. The inner and outer walls 13^a and 14^a and the closure walls 20^a provide a water-chamber 15^a that leads up to a horizontal dome element corresponding in section with the dome element of the sections A and B. The side members or legs of the intermediate section C are connected intermediate their ends by a horizontal tubular member Z that is formed concave on one of its faces as at ⁷⁵ 44, so as to fit against the "nose" portion 28 of the water-chamber X projecting from the front section A of the furnace and the lower wall 45 of this tubular member Z is in the horizontal plane of the bottom wall 27 of ⁸⁰ said chamber X. The concave portion 44 of the tubular member projects beyond the vertical plane of the upright legs of the intermediate member, as seen in Figures 6 and 7 and the portion of the tubular member opposite thereto is set back from the plane of the opposite edges of the legs so as to not close the passageway 33 between the water-chambers X and Y. The intermediate section C is not in communication with the water-chambers and semi-cylindrical portions of the sections A and B and it will be understood that the hot water or steam will be discharged from the dome of the intermediate section through an outlet stub corresponding ⁸⁵ with stubs 25 and leading to the coupling 26 which is changed from a T to a "cross." It will also be understood that the return water is fed back into the intermediate section through the couplings 36 which are likewise changed from T's to "crosses." If it is desired to further enlarge the furnace or increase its capacity, other intermediate sections may be utilized alongside of the section C, and when more than one of these intermediate sections are employed, the dimensions of the elongated passageway 33 may be modified and controlled by omitting the horizontal tubular member Z of the intermediate section that is nearest the water-chamber Y; or, in lieu of omitting this member, the same may be reduced in transverse dimensions.

It will be obvious to others skilled in the art to which this invention pertains that divers modifications or refinements of the structure illustrated may be made without departing from the principles involved, and I therefore desire it understood that all such

changes are fully contemplated as coming within the scope of the appended claims.

What I claim is:—

- 5 1. A boiler furnace comprising a base, a plurality of hollow-wall sections secured together and mounted thereon to provide a fire-pot in their lower portions and having an outlet for the products of combustion, overhanging hollow domes abutting each other 10 at the upper ends of said sections, irregular-shaped water chambers projecting inwardly from the respective sections and overhanging the fire-pot, one of which is below said outlet, one of said chambers having a substantially horizontal base wall and the other chamber having an inclined base wall, and tubes disposed in front of said outlet and communicating at opposite ends with the interior of the adjacent water chamber and 15 overhanging dome above the same.
- 20 2. A boiler furnace comprising oppositely disposed semi-cylindrical sections having hollow walls, one of said sections provided with an outlet for the products of combustion, overhanging semi-circular domes having hollow walls forming continuations of the walls of the respective sections, water-chambers extended inwardly towards each other from the inner walls of said sections, 25 the inner portions of said chambers being adjacent each other, one of said chambers having a wall inclined upwardly from its inner edge and the other chamber having a wall inclined downwardly from its inner edge, and 30 a tube connecting the dome and water chamber of the section provided with the outlet and disposed in the path of the products of combustion passing to said outlet.
- 35 3. A boiler furnace comprising oppositely disposed semi-cylindrical sections having hollow walls, one of said sections provided with an outlet for the products of combustion, overhanging semi-circular domes having hollow walls forming continuations of 40 the walls of the respective sections, water-chambers extended inwardly towards each other from the inner walls of said sections, the inner portions of said chambers being adjacent each other, one of said chambers 45 having a wall inclined upwardly from its inner edge and the other chamber having a wall inclined downwardly from its inner edge, two spaced tubes connecting the dome and water-chamber of the section having the outlet, and a baffle wall extending between said 50 tubes and disposed in the path of the products of combustion passing to said outlet.
- 55 4. A boiler-furnace comprising a base, a plurality of opposing hollow-wall sections secured together and mounted on said base to provide a fire-pot, a chimney flue leading from the upper portion of one of said sections, irregular shaped water chambers overhanging the fire-pot from the sections, the inner portions of the base walls of said cham- 60 bers being contiguous each other whereby to provide a restricted passageway between their inner edges, the walls to the water chambers above the fire-pot being formed to divide the interior of the furnace into upper and lower portions communicating with each other through said passageway, and tubes positioned between one of said water chambers and the upper part of the respective section whereby to retard the movement of the products of combustion approaching the chimney flue.

Signed at Chicago, in the county of Cook and State of Illinois, this 7th day of May, 1926.
